UNITED STATES PATENT OFFICE.

SAMUEL A. BENNER, OF PITTSBURGH, PENNSYLVANIA.

SIDE-FRAME CONSTRUCTION.

1,246,381.

Specification of Letters Patent. Patented Nov. 13, 1917.

Application filed February 26, 1914, Serial No. 821,242. Renewed March 31, 1917. Serial No. 159,025.

To all whom it may concern:

Be it known that I, SAMUEL A. BENNER, a citizen of the United States, and resident of Pittsburgh, in the county of Allegheny and State of Pennsylvania, have invented a new and useful Improvement in Side-Frame Constructions; and I do hereby declare the following to be a full, clear, and exact description thereof.

10 My invention relates to improvements in truck side-frames and is particularly concerned with the construction of a side-frame in which all parts, including the pedestal, are formed of rolled sections of steel.

15 The object of the invention is the production of a side-frame of great strength in proportion to its weight and one in which the parts may be very readily and strongly assembled.

20 A further object is to secure a very material reduction in the cost of manufacture, both in the production of the parts of the frame and also in the labor of assembling.

A further object is to so construct and 25 arrange the parts that the riveting operations will be simplified as much as possible, by arranging the parts so that all riveting will be "open riveting."

Furthermore, the side-frame forming the 30 subject matter of this case has the advantage that the transverse "webs" of the compression and tension members and also of the pedestal are spaced as far as the limits of the construction will allow, from the neutral axis of strain of the frame. This neutral axis, as is well known to persons skilled in this art, is in the line at which the compression and tension strains neutralize each other in a truss of the form here considered,

35 and extends longitudinally of the frame and a little below the center of the pedestal. By so locating the webs of the main truss members of the frame at the maximum distance from this neutral line, the greatest possible 40 strength is secured.

In the drawings, which illustrate a preferred embodiment of the invention, Figure 1 is a section of a form of compression member employed. Fig. 2 is a side elevation. 45 Fig. 3 is a plan view of the side frame. Fig. 4 is a partial elevation and partial vertical section of the side-frame. Fig. 5 is a vertical transverse section on the line 5—5, Fig. 4; Fig. 6 is a transverse section on the line 55 6—6, Fig. 4; Fig. 7 is a section on the line

7—7, Fig. 4; Fig. 8 is a section on the line 8—8, Fig. 4, and Fig. 9 is a section on the line 9—9, Fig. 4.

Referring to Figs. 1 and 2 of the drawing, the compression member of the side-frame is 60 composed of a rolled section comprising a transverse web 1, having upwardly extending flanges 2—2, forming an upwardly opening channel member. Extending down from the web are the flanges 3—3, forming a downwardly opening channel member. The web 1 is extended in to side flanges 4—4. The inside faces of the lower flanges 3—3, are in line with the outside faces of the upper flanges 2—2, thus forming what I term a double - differential channel member for purposes hereinafter described. In forming the compression member, the upper flanges 2—2 are sheared off along the lines 5—5, thus bringing the 65 web to the top or outside at the central portion of the member. These flanges are also sheared along the lines 6—6 for the purpose hereinafter described.

The lower flanges 3—3 are preferably cut 70 away along the lines 7—7. The lateral flanges 4—4 are cut away along the lines 8, Fig. 3, thus producing at the section line 8—8, Fig. 1, a cross-section such as shown in Fig. 8, while at the center the flanges 4—4 are shown in their full width as in the cross-section 5—5, Fig. 5, from the points 9—9, Fig. 3, at which the flanges 4—4 disappear altogether and the depending flanges 3—3 of the compression member are inset in proper dies to bring them to the position shown in the cross-section 7—7, Fig. 7; in other words, directly in alinement with the 75 upper flanges 2—2 on the upper side of the web 1.

The sheared away portions of the flanges 80 3—3 along the lines 7 and flush with the web 1, bring the outer ends of the compression member into the cross-sectional form shown in Fig. 6. In other words, these ends are reduced to simple upwardly opening channel form.

This compression member so sheared, is then bent to the shape shown in Fig. 4.

The tension member of the side-frame is 105 preferably formed of a rolled section such as that illustrated in Fig. 5, and comprises a web 10, the side-walls 11 and laterally extending flanges 12. These lateral flanges are sheared off along the lines 13, Fig. 3, to 110

reduce the ends of the member to the outside width of the side-walls 11 as shown in Fig. 6.

It is to be understood that the inside 5 width of the depending flanges 3 of the compression member is the same initially as that of the side-walls 11 of the tension member. This is primarily for the purpose of 10 accommodating the truck pedestal in the manner hereinafter described.

In assembling the compression and tension members, the channel shaped ends of the compression member are nested within the channel shaped ends of the tension member as shown in Fig. 6. This is rendered 15 possible by the fact that the spacing apart of the upper flanges 2—2 of the compression member is such that the distance between the outer faces of these flanges is equal to 20 the distance between the inner faces of the side-walls 11 of the tension member. It will be noted, however, that the spacing apart 25 of the depending flanges 3 of the compression member is the same as that of the side-walls 11 of the tension member, and for this reason it is necessary to inset or compress those portions 14 of the depending flanges 3—3, which would extend within the channel of the tension member as shown in Fig. 30 4. This compression or insetting is effected at the points 15—15, Fig. 3. The tension member is bent to the shape shown in Fig. 4, and the flanges 2 of the tension members are riveted through and through to the side-walls 11 of the compression member.

It is to be understood, however, that instead of insetting the depending flanges 3—3 to enable the portions 14 thereof to enter the channel of the tension member, 40 said flanges may be sheared along the lines 16—16 so that they will stop short of the tension member. The former construction has the advantage, however, that the insertion of the ends of these flanges 3—3 45 within the channel of the tension member, lends great strength and lateral support to the compression member at the junction of the two.

From the construction just described, it 50 will be seen that the web of the compression member is brought to the top at the central portion of the side-frame and extends from the central portion at either end down to the junction with the web of the tension member. Moreover, the depending flanges 55 of the compression member intermediate its ends, form a downwardly opening channel for the reception of the pedestal. Likewise, the web of the tension member is at the 60 bottom at the central portion of the frame and extends from that point to the junction with the web of the compression member and the side-walls of the tension member 65 form an upwardly opening channel for the reception of the pedestal.

Furthermore, inasmuch as the distance between the depending flanges 3 of the compression member at the central portion thereof, is the same as that between the side-walls of the tension member, it is possible 70 to employ a pedestal of the same width throughout its perimeter, thus simplifying the pedestal and therefore reducing materially its cost.

In practice I have found that the most 75 economical and at the same time strong form of pedestal, may be made of a simple rolled channel shaped section, such as that shown in Fig. 4, and the strength of this pedestal is enhanced by having the web 17 80 thereof at the outside with the flanges 18 opening inwardly. This construction also greatly facilitates the riveting of the upper and lower cords of the pedestal to the compression and tension members, for, as will 85 be seen in Fig. 5, the flanges 18 of the pedestal are snugly embraced by the depending flanges 3 of the compression member, and these walls and flanges form a downwardly opening channel within which 90 the riveting may be easily accomplished. In like manner, the flanges 18 of the pedestal are snugly embraced by the side-walls 11 of the tension member, thus forming an upwardly opening channel within which the 95 riveting may be easily effected.

It will be seen, therefore, that all of the riveting necessary to secure these three major parts of the side-frame together, is open riveting readily accessible to the riveting tools.

The pedestal may be provided with the usual wear plates for the truck bolster by riveting short channel sections 19 to the flanges 18 of the pedestal.

The entire truck side-frame, therefore, consists of a compression member formed of what may be termed a double differential channel member, meaning thereby, a double channel member in which one of the channels is of less width than the other; a tension member consisting of a simple rolled channel section having lateral flanges such as 12, and a pedestal member consisting of a simple rolled channel section of a width to fit and be seated within the downwardly opening channel of the compression member and the upwardly opening channel of the tension member. The lateral flanges 4—4 110 of the compression member and the corresponding flanges 12—12 of the tension member serve greatly to strengthen the structure against lateral and torsional strains. Furthermore, the lateral flanges 12 of the tension member form a broad bearing seat 115 for the spring base-plank, which may be readily riveted to these flanges on the opposite side-frames.

The double channel shaped compression member, sheared and bent as described, may 120 125 130

also be employed with advantage as a truck or car bolster by simply providing the central portion thereof with a suitable form of center bearing plate, and by securing at the 5 ends side bearing plates and bolster guides. Such parts are not specifically illustrated but it is to be understood that this invention is intended to cover not only a side-frame including such compression member, but 10 also such member *per se* considered as a car part.

While I have herein shown and described a particular embodiment of the invention, it is to be understood that the same may be 15 altered in details and relative arrangements of parts within the scope of the appended claims.

What I claim is:

1. A truck side frame having its compression and tension members formed of rolled channel shaped sections, one of which has channel shaped portions narrower than those of the other, so that the ends of one member may nest within the corresponding ends of 25 the other, either one or both of said channel shaped sections being of double channel differential shape.

2. A truck side-frame having its compression member formed of a rolled differential 30 channel shaped section, and a tension member formed of a rolled channel shaped section, the upper channel of the compression member being of less width than that of the tension member whereby the upwardly opening channel shaped ends of the compression member may nest within the channel shaped ends of the tension member, the upper flanges of the compression member being sheared at the central portion thereof, to 35 bring the central portion of the web of the compression member toward or to the top.

3. A truck side-frame having its compression member formed of a rolled differential channel shaped section, and a tension member 45 formed of a rolled channel shaped section, the upper channel of the compression member being of less width than that of the tension member whereby the upwardly opening channel shaped ends of the compression member may nest within the channel shaped ends of the tension member, the upper flanges of the compression member being sheared at the central portion thereof to bring the central portion of the web of the 50 compression member toward or to the top, the lower flanges of the compression member being sheared off adjacent the ends thereof to permit said ends to be nested within the corresponding ends of the tension member.

4. A truck side-frame having its compression member formed of a rolled differential channel shaped section, and a tension member 55 formed of a rolled channel shaped section, the upper channel of the compression member being of less width than that of the tension member whereby the upwardly opening channel shaped ends of the compression member may nest within the channel

of the tension member whereby the upwardly opening channel shaped ends of the compression member may nest within the channel shaped ends of the tension member, the upper flanges of the compression member being sheared at the central portion thereof to bring the central portion of the web of the compression member toward or to the top, the lower flanges of the compression member forming at the central portion thereof a downwardly opening channel to receive the upper side of the pedestal. 70

5. A truck side-frame having its compression member formed of a rolled differential channel shaped section, and a tension member formed of a rolled channel shaped section, the upper channel of the compression member being of less width than that of the tension member whereby the upwardly opening channel shaped ends of the compression member may nest within the channel shaped ends of the tension member, the upper flanges of the compression member being sheared at the central portion thereof to bring the central portion of the web of the compression member toward or to the top, the downwardly opening channel portion at the center of the compression member and the upwardly opening channel portion at the center of the tension member forming 95 seats to embrace the upper and lower portions respectively of the pedestal member.

6. A truck side-frame having its compression member formed of a rolled differential channel shaped section, and a tension member formed of a rolled channel shaped section, the upper channel of the compression member being of less width than that of the tension member whereby the upwardly opening channel shaped ends of the compression member may nest within the channel shaped ends of the tension member, the upper flanges of the compression member being sheared at the central portion thereof to bring the central portion of the web of the compression member toward or to the top, the compression and tension members having oppositely opening channel portions at the central portions thereof, and a pedestal member composed of a rolled channel shaped section having its web at its outside, said pedestal member being seated within the channel portions of the compression and tension members respectively, with its web in contact with the webs of the compression and tension members respectively. 110

7. A truck side-frame having its compression member formed of a rolled differential channel shaped section, and a tension member formed of a rolled channel shaped section, the upper channel of the compression member being of less width than that of the tension member whereby the upwardly opening channel shaped ends of the compression member may nest within the channel

- shaped ends of the tension member, the upper flanges of the compression member being sheared at the central portion thereof to bring the central portion of the web of the 5 compression member toward or to the top, said compression and tension members having oppositely opening channel portions at the central parts thereof respectively, and a pedestal formed of a rolled channel section 10 of the same width throughout and having its web at the outside thereof, said pedestal being adapted to be seated within the central channel portions of the compression and tension members, respectively.
- 15 8. A truck side-frame having its compression member formed of a rolled differential channel shaped section, and a tension member formed of a rolled channel shaped section, the upper channel of the compression member being of a less width than that of the tension member whereby the upwardly opening channel shaped ends of the compression member may nest within the channel shaped ends of the tension member, 20 the upper flanges of the compression member being sheared at the central portion thereof to bring the central portion of the web of the compression member toward or to the top, said compression and tension members respectively having oppositely opening central channel members of the same inside width, a pedestal formed of a rolled channel section of uniform width throughout having its web at the outside 25 thereof whereby said pedestal member may be seated within said channel portions of the compression and tension members respectively, with the web of said pedestal in contact with the webs of the compression and 30 tension members respectively.
- 35 9. A truck side-frame having its compression member formed of a rolled differential channel shaped section having the side walls of the lower channel sheared off at the ends 40 of the section, and having the side walls of the upper channel sheared off at the center portion, a tension member formed of a rolled channel shaped section, of a width to snugly receive the upper channel shaped end portions of the compression member whereby 45 said ends may be nested snugly within the channeled end portions of the tension member, and whereby the web of the compression member will be at the top at the center 50 of said member and the web of the tension member will be at the bottom throughout said member.
- 55 10. A truck side-frame having its compression member formed of a rolled differential channel shaped section having its web extended laterally at either side of the channel portions to form strengthening flanges and a tension member formed of a channel shaped section, the lower flanges and the 60 lateral flanges of said compression member 65

being sheared off adjacent the ends of said member whereby said ends may be nested within the channel shaped ends of the tension member.

11. A truck side-frame having its compression member formed of a rolled differential channel shaped section having its web extending laterally at either side of the channel portions to form strengthening flanges and a tension member formed of a channel shaped section, the lower flanges and the lateral flanges of said compression member being sheared off adjacent the ends of said member whereby said ends may be nested within the channel shaped ends of the tension member, the side walls of the tension member having laterally extending flanges to laterally reinforce said member and to form a broad bearing for the spring base plank. 70

80 12. A truck side-frame having its compression member formed of a rolled differential channel shaped section having its web extending laterally at either side of the channel portions to form strengthening flanges and a tension member formed of a channel-shaped section having its side-walls flanged laterally, the lower flanges and the lateral flanges of said compression member being sheared off adjacent the ends of said member whereby said ends may be nested within the channel shaped ends of the tension member, the lateral flanges of said tension member being sheared off at the ends to eliminate material not necessary for effective strength and to afford clearance for 85 the wheels. 90

95 13. A truck side-frame having its compression member formed of a rolled differential channel shaped section the side walls 100 of the lower channel being sheared off adjacent the ends of said section, the side walls of the upper channel being sheared off at the center to bring the web of said section toward or to the top at the center 105 thereof and leave upwardly opening channel shaped ends for said member and a downwardly opening channel shaped central portion for said member, a tension member formed of a channel shaped section of an 110 inside width equal to the inside width of the downwardly opening channel shaped portion of the compression member, and a pedestal formed of a rolled channel section 115 of uniform width throughout whose web is 120 at the outside thereof, said pedestal being adapted to be received within the downwardly opening channel of the compression member and the upwardly opening channel of the tension member whereby the side 125 walls of said pedestal may be riveted to the side walls of the compression and tension members, respectively. 130

14. A truck side-frame comprising a compression member having upwardly opening

- channel shaped portions at its ends and a downwardly opening channel shaped portion at its center whereby the web of said member forms the bottom walls thereof at 5 the ends of said member and the top wall thereof, at the center of said member and a tension member formed of a rolled channel shaped section within the channel shaped ends of which the channel shaped ends of 10 the compression member are received and secured.
15. A truck side-frame comprising a compression member having upwardly opening channel shaped portions at its ends and a downwardly opening channel shaped portion at its center whereby the web of said member forms the bottom walls thereof at the ends and the top wall thereof at the center, and a tension member formed of a rolled channel shaped section within the channel shaped ends of which the channel shaped ends of the compression member are received and secured, and a pedestal formed of a channel shaped section adapted to be seated 20 and secured within the central channel shaped portions of the compression and tension members, respectively.
25. A car part comprising a double channel shaped rolled section, having upwardly opening channel shaped portions at its ends and a downwardly opening channel shaped portion at its center whereby the web of said section extends adjacent the bottom at the ends and along the top of the section at the central portion thereof, and extends diagonally between said end portions and said central portion.
30. A car part comprising a double differential channel shaped rolled section, having upwardly opening channel shaped portions at its ends and a downwardly opening channel shaped portion at its center whereby the web of said section extends along the bottom at the ends and adjacent the top of the section at the central portion thereof and extends diagonally between said end portions and said central portion.
35. A truck side-frame having its compression member formed of a rolled differential channel shaped section and a tension 40 member formed of a rolled channel shaped section, the upper channel of the compression member being of less width than that of the tension member, whereby the upwardly opening channel shaped ends of the compression member may nest within the channel shaped ends of the tension member, the inside width of the downwardly opening channel portion of said compression member being initially the same as that of the tension member, the side walls of said downwardly opening channel portions of the compression member being sheared off adjacent the ends of said member and the sheared ends of said side walls being inset to fit 45 within the adjacent portions of the tension member.
45. A truck side-frame having its compression member formed of a rolled differential channel shaped section, the upper channel of the compression member being of less width than that of the tension member whereby the upwardly opening channel shaped ends of the compression member may nest within the channel shaped ends of the tension member, the upper flanges of the compression member being sheared at the central portion thereof to bring the central portion of the web of the compression member toward or to the top, said compression 50 and tension members respectively having oppositely opening central channel members of the same inside width, a pedestal formed of a rolled channel section, the outside width of pedestal being same as inside width of opposite channel parts of compression and tension members, whereby said pedestal member may be seated within said channel portions of the compression and tension members respectively, with the web of said pedestal in contact with the webs of the compression and tension members respectively.
55. A truck side-frame having its compression member formed of a rolled differential channel shaped section and a tension 60 member formed of a rolled channel shaped section, the upper channel of the compression member being of less width than that of the tension member, whereby the upwardly opening channel shaped ends of the compression member may nest within the channel shaped ends of the tension member, the inside width of the downwardly opening channel portion of said compression member being initially the same as that of the tension member, the side walls of said downwardly opening channel portions of the compression member being sheared off adjacent the ends of said member and the sheared ends of said side walls being inset to fit 65 within the adjacent portions of the tension member.
65. A truck side-frame having its compression member formed of a rolled differential channel shaped section, the upper channel of the compression member being of less width than that of the tension member whereby the upwardly opening channel shaped ends of the compression member may nest within the channel shaped ends of the tension member, the upper flanges of the compression member being sheared at the central portion thereof to bring the central portion of the web of the compression member toward or to the top, said compression 70 and tension members respectively having oppositely opening central channel members of the same inside width, a pedestal formed of a rolled channel section, the outside width of pedestal being same as inside width of opposite channel parts of compression and tension members, whereby said pedestal member may be seated within said channel portions of the compression and tension members respectively, with the web of said pedestal in contact with the webs of the compression and tension members respectively.
75. A truck side-frame having its compression member formed of a rolled differential channel shaped section, the upper channel of the compression member being of less width than that of the tension member whereby the upwardly opening channel shaped ends of the compression member may nest within the channel shaped ends of the tension member, the upper flanges of the compression member being sheared at the central portion thereof to bring the central portion of the web of the compression member toward or to the top, said compression 80 and tension members respectively having oppositely opening central channel members of the same inside width, a pedestal formed of a rolled channel section, the outside width of pedestal being same as inside width of opposite channel parts of compression and tension members, whereby said pedestal member may be seated within said channel portions of the compression and tension members respectively, with the web of said pedestal in contact with the webs of the compression and tension members respectively.
80. A truck side-frame having its compression member formed of a rolled differential channel shaped section and a tension 85 member formed of a rolled channel shaped section, the upper channel of the compression member being of less width than that of the tension member, whereby the upwardly opening channel shaped ends of the compression member may nest within the channel shaped ends of the tension member, the inside width of the downwardly opening channel portion of said compression member being initially the same as that of the tension member, the side walls of said downwardly opening channel portions of the compression member being sheared off adjacent the ends of said member and the sheared ends of said side walls being inset to fit 90 within the adjacent portions of the tension member.
85. A truck side-frame having its compression member formed of a rolled differential channel shaped section and a tension member formed of a rolled channel shaped section, the upper channel of the compression member being of less width than that of the tension member, whereby the upwardly opening channel shaped ends of the compression member may nest within the channel shaped ends of the tension member, the inside width of the downwardly opening channel portion of said compression member being initially the same as that of the tension member, the side walls of said downwardly opening channel portions of the compression member being sheared off adjacent the ends of said member and the sheared ends of said side walls being inset to fit 95 within the adjacent portions of the tension member.

In testimony whereof, I the said SAMUEL A. BENNER, have hereunto set my hand.

SAMUEL A. BENNER.
